COMBINED ELECTRIC SHAVER AND STORAGE BASE

Melvin H. Boldt, Glenview, Ill., assignor to Schick Electric Inc., Lancaster, Pa., a corporation of Delaware

Filed July 18, 1968, Ser. No. 12,823

Term of patent 14 years

Int. Cl. D28—03

U.S. Cl. D95—3

FIG. 1

FIG. 7

FIG. 2

FIG. 8

FIG. 3

FIG. 4

FIG. 6

FIG. 5

FIG. 9

FIG. 1 is a perspective view of a combined electric shaver and storage base showing my new design in its nonoperating position wherein the front, top, and one side thereof are visible;

FIG. 2 is a perspective view similar to the view in FIG. 1 wherein the back, bottom and remaining side thereof are visible;

FIG. 3 is a perspective view of the electric shaver thereof, the storage base having been omitted for purposes of illustration;

FIG. 4 is a rear elevational view of the shaver as shown in FIG. 3;

FIG. 5 is an elevational view thereof illustrating the side not visible in FIG. 3;

FIG. 6 is a top view thereof;

FIG. 7 is a bottom view thereof;

FIG. 8 is a perspective view thereof similar to the view in FIG. 3 but with the shaver in its operating posi-

FIG. 9 is a front, top perspective view of the storage base.

I claim:

The ornamental design for a combined electric shaver and storage base, substantially as shown and described.
